ASSIGNORS TO CHARLES H. JOY, SR., OF CHICAGO, ILLINOIS

METHOD OF FORMING BEARINGS

Application filed October 22, 1926. Serial No. 143,490.

This invention relates to a new and improved method of forming a bearing.

One of the objects of our invention is to provide a new method for forming a bearing which will lessen the cost of production.

Another object of our invention is to provide a new method for forming a bearing which will reduce the waste and the number of operations to a minimum.

Another object is to provide a new method which will improve the product.

A further object is to provide an improved method of forming a bearing member from flat stock by a cold working process.

Further objects will appear from the description and claims. In the drawings in which our invention is illustrated:

Figure 1 is a vertical sectional view showing the blank and the special tool and die for performing the first step in the operation;

Fig. 2 is a similar view showing the beginning of the succeeding or second step in the operation;

Fig. 2A is a showing of an arcuate gradient as contrasted with a gradient of different inclinations acting successively;

Fig. 3 is a similar view showing the completion of the second step;

Fig. 4 is a similar view showing the beginning of the third or final step;

Fig. 5 is a vertical sectional view of the resultant bearing; and

Fig. 6 is a vertical sectional view of the sliding punch.

Referring to the drawings, the following is a description of our cold work process for turning flat discs of a high carbon chrome steel into annular rings for ball bearings. First, the blank 10 is punched from a steel strip stock of a definite thickness and a hole pierced in the center thereof. The outside diameter, the diameter of the hole, and the thickness of the metal are all co-relative, and the finished annular ring is definitely proportional to the original dimensions of the blank, although these proportions vary somewhat for each different size of annular ring.

This blank or flat disc 10, with its inside hole, thickness, and outside diameter carefully and properly proportioned one to the

other, is placed in the nest 11 of the die 12. A straight side punch 13, whose radius on its working corner is predetermined, and whose diameter is larger by a definite amount than the inside hole 14, forces it through the die throat 15, which, at predetermined places, contains progressive angle tapers that serve to guide and compress the disc as it turns through its operation.

Toward the bottom where the punch pushes through the hole and the shoulder of the punch engages the folded edge of the disc, the tapers are made to give a compression support to keep the smaller diameter of the drawn piece from breaking. This position is at about the end of the stroke, as shown in dotted lines, and the turned disc is pushed from here into a container or basket by the piece following. The die throat has several tapers of different inclinations which act progressively, and at no time stop the movement of the ring past their faces, while each taper with its predetermined angle is essential in successfully turning the blank.

These tapers of different inclinations will hereinafter be referred to as "progressive tapers." As the piece passes over these tapers, the work in the piece is gradually increased, that is, with each succeeding taper, a greater strain is set up in the piece. However, the work or strain in the piece is the greatest upon its initial movement into a new angle of inclination, whereafter the work or strain is relieved in its further movement along the face of this inclination.

The aforementioned relief is clearly illustrated by the showing in Fig. 2A, wherein several different inclinations which act successively are contrasted with an arcuate inclination. It will be apparent that were the work gradually increased in the piece with no relief, an arcuate gradient would result; whereas, if the work were gradually increased in the piece with an allowance for relief at stated intervals, a gradient composed of successive tapers of different inclinations would result.

As the result of these progressive tapers, the piece is deformed to the limit of its elasticity, as at A, where the action of the stress

is at its maximum, whereafter the action of the stress is reduced and the strain in the piece is relieved by means of the tapered face portion until the point B is reached, 5 where the action of the stress is again greater and the piece is further deformed to the limit of its elasticity and the aforementioned action is repeated.

Referring to Fig. 2A, it will be seen that the 10 die at the various points A, B, and C, provides in effect a series of annular fulcrums at these points about which the ring is bent or turned by the action of the punch 13. The blank 10 first tilts or turns about the annular fulcrum through the point A under the action of the punch 13 until the lower outer face of the blank comes into contact with the die at the point B; thereafter, the blank (which is now in the form of a conical collar) tilts or 15 turns about the annular fulcrum through the point B until the outer surface of the blank or collar comes into contact with the die at the point C; thereafter, the blank is bent or turned about the annular fulcrum through 20 the point C. During this operation the sides of the conical blank or collar increase in steepness progressively.

Before the next operation, the rings are annealed so the strains of the first operation 30 shall be removed; in fact, an annealing operation is necessary between each action.

In this second operation the piece is inverted, so the taper end 16 with the smaller diameter engages the punch and the larger 35 diameter 17 rests in the die nest 11^a. The throat of this also contains a series of progressive tapers which compress and iron the metal in much the same manner as the first operation, but of course the tapers have different 40 angles, the work on the metal is much more severe because an ironing action is introduced in this operation. Here the metal is made to flow upward against the direction of the punch "down travel" and the reaction force 45 working in the opposite direction, grips the side of the punch with such great pressure that in order to avert rupture it must be relieved by a sliding punch 18, which, independent of the punch shoulder, moves with 50 and yields to the force. This gripping force acts on the punch side as the shoulder 19 of the punch is forcing the ring through the die, and it pulls downward on the side with greater velocity than the movement of the shoulder 55 of the punch through the downward part of the cycle.

The ring in this operation is reduced in outside diameter and thickness, and increased in height. It is ironed to its new form by 60 means of two factors; first, the punch which sizes the inside diameter, and second, the tapers in the throat of the die which sizes the outside diameter. The ring is now submitted to the important annealing operation, heretofore referred to.

After the shoulder 19 of the punch pushes the ring ahead of it, it will be seen that the lower or front edge of the collar or ring actually moves faster than the shoulder 19 itself because of the fact that the distance between the adjacent surface of the die and punch is less than the average thickness of the metal in the ring or collar so that the material in the collar is contracted and squeezed and forced to flow faster than the shoulder which is forcing it downwardly. 70

In the third operation, the ring is worked to its exact machining dimensions for a ball bearing race. A sliding punch and a die with the correct set of progressive tapers iron the 80 metal to a uniform thickness throughout its length, square the corners, and size to a predetermined limit the inside diameter, the outside diameter, and the height.

This alternate cold working and annealing 85 treatment breaks up the lanular condition of the perlite and forms an envelope about the carbide found in commonly annealed stock. This structure is desirable because in the attendant annealing treatment there is an incomplete absorption of the spheroidal carbide and the result is a condition of structure analogous to that in bearing metals, such as babbitt and the like. In this method the martensite or body of steel is stiffened and 90 supported by the carbide remaining undisolved, the latter being very hard and capable of withstanding extreme wear. The reduction or ironing of the metal within limits and the use of a predetermined pressure in the 95 ironing operations are important features. 100

Tests show that the hardness of the material is greatly increased by this method and that no internal strains are set up as in other methods. 105

The successive alternate ironing and annealing breaks down the internal strains due to the prior treatment of the metal at the mill.

The sliding punch 18 comprises a body portion 20 of a usual type having a central core portion 21 which is yieldably supported in said body portion and extends downwardly therefrom. The core portion 21 preferably consists of a one-piece casting of two different diameters whereby a shoulder 22 is formed. 110 The smaller diameter of the core portion is supported in a central aperture 23 in the main body portion while the larger diameter of the core portion is countersunk in a second central aperture 24 in the main body portion. 115 One end of a spring 25 is fastened to a screw member 26, which latter is mounted in an insert 27 at the upper end of the body portion 20 and is stationary therewith, while the other end of said spring 25 is secured to the 120 movable core portion 21. This spring normally acts to hold the shoulder 22 of the core portion 21 against its seat.

The core portion 21 also contains an elongated aperture therethrough and horizontal. 125

ly thereof through which a pin 28 extends to be secured at its outer ends to the main body portion 20. This pin is for the purpose of limiting the movement of the core portion 5 relative to the main body portion. The action of this sliding punch has been hereinbefore referred to. In the ironing action, the metal is made to flow upwardly against the direction of the downward movement of 10 the punch and the reaction force working in the opposite direction grips the side of the core portion 21 with such great pressure that in order to avert rupture, said core portion moves with and yields to this force against 15 the action of the spring 25 and thereby moves this core portion downwardly with greater velocity than the movement of the shoulder 19 of the punch.

This application is a continuance as to common disclosure of our prior applications Serial Numbers 688,693, filed January 26, 1924, and 67,708, filed November 9, 1925.

We claim:

1. A method of forming an annular bearing member comprising forming a collar from sheet metal, inserting a cylindrical forming member into said collar in such manner that its axial movement is controlled by 25 its engagement with said collar and forcing 30 said collar and cylindrical forming member through a die, and during this operation exerting pressure on the edge of the collar to force it through the die, the distance between the adjacent surfaces of the die and 35 cylindrical forming member being less than the average thickness of the metal in the collar before the operation, whereby the distance between the edges of the collar is increased as the collar is pushed through the die.

40 2. A method of forming an annular bearing member comprising forming a collar from sheet metal, inserting a cylindrical forming member into said collar in such manner that its axial movement is controlled by 45 its engagement with said collar and forcing 50 said collar and cylindrical forming member through a die, and during this operation exerting pressure on the edge of the collar to force it through the die, the distance between 55 the adjacent surfaces of the die and cylindrical forming member being less than the average thickness of the metal in the collar before the operation, whereby the front edge of the collar advances faster than the edge on which pressure is being exerted.

3. A method of making an annular bearing member comprising making a flat sheet metal ring, supporting the outer edge of said ring on an annular fulcrum, exerting pressure on the inner part of said ring while cold to bend it about said fulcrum into a substantially conical collar, annealing said collar, inserting a cylindrical forming member into said collar in such manner that its axial movement is controlled by its engagement

with said collar, and forcing said collar and cylindrical forming member through a die, and during this operation exerting pressure on the edge of the collar, the distance between adjacent surfaces of the die and cylindrical forming member being less than the average thickness of the metal in the collar before the operation whereby the front edge of the collar advances faster than the edge on which pressure is exerted.

In witness whereof we have hereunto subscribed our names.
